UNITED STATES PATENT OFFICE.

WILLIAM H. NAUMAN, OF PHILADELPHIA, PENNSYLVANIA.

FOLDING CRATE.

1,141,574.

Specification of Letters Patent.

Patented June 1, 1915.

Application filed April 22, 1914. Serial No. 833,789.

To all whom it may concern:

Be it known that I, WILLIAM H. NAUMAN, a citizen of the United States, residing at Philadelphia, in the county of Philadelphia and State of Pennsylvania, have invented certain new and useful Improvements in Folding Crates, of which the following is a specification, reference being had to the accompanying drawings.

10 This invention relates to new and useful improvements in crates and more particularly to that class of crates which are foldable to reduce the size of the same for shipping or storing.

15 An object of this invention is the provision of a folding crate which comprises a bottom having side and end walls hingedly connected thereto, the end walls also having top sections hingedly connected thereto 20 which are adapted to close the top of the crate.

Another object of this invention is the provision of a folding crate comprising a bottom having upstanding flanges extending from its side and end edges, the flanges having side and end walls hingedly connected thereto, each of the side walls comprising two sections hingedly connected together, the end walls carrying means for holding the sections of the side walls in upright position, and each of the end walls also carrying a section of the cover for closing the upper end of the crate.

A still further object of this invention is 35 the provision of a folding crate comprising a bottom having side and end walls rigidly connected thereto, the end walls having sections of the cover hingedly connected thereto, the side walls being adapted to be folded 40 inwardly toward the bottom of the crate, and the end walls and cover sections being adapted to be folded on top of the folded side walls so that the size of the crate is materially reduced for convenience in shipping 45 or storing the same.

With these and other objects in view, my invention consists in the novel construction, combination and arrangement of parts to be hereinafter more fully described, claimed, 50 and illustrated in the accompanying drawings, in which—

Figure 1 is a perspective view of my improved crate, showing the same in set up position; Fig. 2 is a vertical section of the 55 same; Fig. 3 is a sectional view on the line 3—3 of Fig. 1; Fig. 4 is a fragmentary top

plan view of one of the side walls; Fig. 5 is a fragmentary top plan view, showing the manner of connecting the side and end walls; Fig. 6 is a perspective view of the 60 crate in folded position; and Fig. 7 is a sectional view on the line 7—7 of Fig. 6.

Referring more particularly to the drawings, the numeral 1 designates the bottom of the crate which is formed with upstanding 65 side flanges 2 at its opposite side edges, and upstanding end flanges 3 at its opposite end edges, the end flanges being of slightly greater height than the side flanges. Connected to the upper edge of each of the side 70 flanges 2 is a side wall 4 and each of the side walls comprising a pair of sections 5 which are hingedly connected together so that the upper section of each side wall may be folded inwardly upon the lower section thereof. 75 The ends of the side walls 4 terminate slightly short of the end flanges 3 and hingedly connected to the upper edges of the end flanges are the end walls 6, each of the end walls 6 being provided at its opposite side 80 edges with inwardly extending spaced guide plates 7 for engagement with the opposite faces of the sections 5 of the side walls at their opposite ends to prevent inward movement or folding of the side walls when the 85 crate is in set up position. Connected adjacent to the opposite ends of the upper sections of the side walls are the loops or staples 8 and pivotally connected to the end walls adjacent their upper edges are hooks 90 9 for engagement with the loops 8 on the side walls to prevent outward swinging of the end walls when the crate is in set up position.

Formed in the inner face of each of the 95 side flanges 2 intermediate of its ends is a vertically disposed groove 10, and formed in the inner faces of the sections 5 of the side walls 4 are similar grooves 11, the grooves 10 and 11 being adapted to register at their 100 ends when the side walls are in upright position. Connected to the sections 5 of the side walls of the side flanges 2 on opposite sides of the grooves are guide plates 12, the opposing edges of which project over the 105 grooves in spaced relation from each other, and mounted in the aligned grooves when the side walls are in upright position are partition plates 13 which are provided with oppositely extending flanges 14 at their ends, the flanges being adapted to engage behind the projecting portions of the guide plates 110

12, the flanges 14 serving to rigidly maintain the partition plate in position in the crate and also to additionally brace the side walls vertically when the crate is in set up position.

Hingedly connected to the outer edges of the end walls 6 of the crate are the top sections 15 and 16, the sections 15 and 16 being adapted to engage at their opposite sides 10 against the upper edges of the upper sections 5 of the side walls 4 when the crate is in set up position, and the sections 15 and 16 carrying inwardly extending plates 17 on the opposite side edges which are adapted to engage 15 the outer faces of the outer sections 5 to form tight joints at the top of the crate. The opposing edges of the sections 15 and 16 when the top is closed are adapted to fit closely adjacent each other, and connected to 20 the outer face of the section 15 at its outer extremity is a strip 18 which projects outwardly beyond the section 15, the strip being adapted to engage over the outer face of the section 16 at its opposing edge to provide 25 a water tight joint between the sections of the top.

Formed in the outer face of the strip 18 is a longitudinal groove 19 in which is mounted a locking rod 20, the intermediate 30 portion of which is looped as at 21, and the opposite ends of which project outwardly through the opposite ends of the strip and are offset laterally as at 22 to form locking lugs.

35 A pair of plates 23 are secured at their opposite longitudinal edges to the outer face of the strip 18, the intermediate portion of each plate being formed with a longitudinally extending crimped portion 24 to receive the rod 20, whereby the locking rod is 40 rotatably connected to the outer face of the strip.

Connected to the outer face of each outer section 5 of the end walls are keeper plates 45 25, the plates projecting beyond the outer edges of the side walls and being provided with hooked portions 26 to receive the locking lugs of the rod 20 whereby the top sections are maintained in close position. Secured in the outer face of the section 16 of the top adjacent its free edge is a staple 27 50 over which the looped portion 21 of the locking rod 20 is adapted to engage, so that a lock 28 of any desired construction may be secured in the staple above the looped portion 21 to securely lock the top sections against the upper edges of the side walls.

60 A crate constructed in accordance with my invention is particularly adapted for use in packing eggs, the egg nests (not shown) being adapted for disposal on the opposite sides of the partition plates 13 and when it is desired to fold my improved crate, the top sections 15 and 16 are swung to an open 65 position and the egg nests removed from the

body of the crate. With the top sections in open position, the partition plates 13 are removed from engagement with the side walls of the said flanges of the crate and placed in the bottom of the crate together with the 70 egg nests, whereupon the hooks 9 are removed from engagement with the loops 8 on the side walls, so that the outer sections of the side walls will be folded against the inner sections thereof and the folded sections 75 of the side walls swing inwardly within the flanges of the bottom of the crate.

It will be apparent that in folding the device, the hinged connection between the end walls 6 and the flange 3 will be sufficiently 80 loose to permit of the end walls being pushed outwardly sufficiently so that the ends of the side walls can be removed from behind the flanges 7. With the side walls in folded position, the end wall 6 which is connected to the shorter of the end flanges 3 and the section of the top connected thereto are swung inwardly to rest upon the folded side walls, whereupon the other end wall 6 and the section 15 of the top are swung downwardly and inwardly upon the first mentioned end wall and top section, and in this position the size of the crate is materially reduced as illustrated in Fig. 6 of the drawings. 90

To lock the crate in folded position, a staple 29 is secured in the outer face of one of the end walls 6, adjacent its inner end, so that when the crate is in folded position, the loop 21 of the locking rod 20 may be engaged over the staple 29, and the lock 28 passed through the staple so that the crate is securely locked in knocked down or folded position. 95

From the above description, taken in connection with the accompanying drawings, it will be seen that I have provided a folding crate which comprises a minimum number of parts whereby the same may be cheaply manufactured, and one which may be readily 100 locked in set up position or locked in folded position, the crate in the latter position being materially reduced in size.

Having thus fully described my invention, what I desire to claim and secure by Letters 110 Patent is:

1. A folding crate including a bottom having upstanding side and end flanges, side and end walls hingedly connected to said side and end flanges, means connecting said side and end walls when in set up position, said side walls having vertically disposed grooves arranged in opposed relation, guide plates secured upon opposite sides of the grooves, a division board having oppositely disposed flanges formed in each side thereof and adapted to be movably mounted behind said guide plates, top sections hingedly connected to the end walls and adapted to fold inwardly, a rotatable rod carried by one of 120

the top sections and having offset portions, and hook members adapted to engage over the offset portion at the ends of the rods to retain the top sections in their closed positions.

2. A folding crate consisting of a bottom having upstanding side and end flanges, sectional side and end walls hingedly connected to said side and end flanges, the side walls and side flanges being provided with vertically disposed grooves arranged in opposed relation, guide plates secured upon opposite sides of the grooves, a division board having opposed flanges formed at opposite side edges and adapted to be engaged behind said guide plates, a sectional cover, each of said sections being hingedly connected to the end walls and adapted to fold inwardly upon the division board, a strip formed at

the outer extremity of one of the top sections and adapted to project beyond the opposite top section when in a closed position, a rotatable rod carried by the strip, offset portions formed at the ends of said rod, catch members secured to the side walls, whereby the offset portions of the rod will engage beneath said catch members upon the rotation of the rod, a loop formed at the intermediate portion of the rod, and means engaging the loop for holding the rod against rotation after the ends thereof have been engaged with the hooks.

In testimony whereof I hereunto affix my signature in the presence of two witnesses.

WILLIAM H. NAUMAN.
